(73) Assignee: **Facebook Technologies, LLC**, Menlo Park, CA (US)

(57) **CLAIM**

(**) Term: **15 Years**

We claim the ornamental design for a depth mapping device, as shown and described.

(21) Appl. No.: **29/643,141**

(22) Filed: **Apr. 4, 2018**

DESCRIPTION

(51) **LOC (12) Cl.** 10-04

FIG. 1 is a top isometric view of a depth mapping device showing the new design.

(52) **U.S. Cl.** USPC **D10/65**

FIG. 2 is a front view thereof.

(58) **Field of Classification Search**

USPC D10/65, 70

CPC G01B 3/28

See application file for complete search history.

FIG. 3 is a back view thereof.

FIG. 4 is a left view thereof.

FIG. 5 is right view thereof.

FIG. 6 is a top view thereof; and,

FIG. 7 is a bottom view thereof.

The broken lines in the figures form no part of the claimed design.
